UNITED STATES PATENT OFFICE.

ANDREW MCKENZIE, OF PROVIDENCE, RHODE ISLAND, ASSIGNOR OF TWO-THIRDS TO JOSEPH M. MANN AND ELLIS C. BEUZARD, JR., OF PROVIDENCE, RHODE ISLAND.

LAMP-SOCKET FOR INCANDESCENT ELECTRIC LAMPS.

SPECIFICATION forming part of Letters Patent No. 691,563, dated January 21, 1902.

Application filed April 29, 1901. Serial No. 58,029. (No model.)

To all whom it may concern:

Be it known that I, ANDREW MCKENZIE, a citizen of the United States, residing at Providence, in the county of Providence and State 5 of Rhode Island, have invented certain new and useful Improvements in Lamp-Sockets for Incandescent Electric Lamps; and I do declare the following to be a full, clear, and exact description of the invention, such as will 10 enable others skilled in the art to which it appertains to make and use the same.

The invention relates to lamp-sockets for incandescent electric lamps.

The object of the invention is to provide a 15 lamp-socket which shall be simple of construction, durable in use, comparatively inexpensive of manufacture, and by means of which the lamps may be expeditiously connected to and disconnected from the socket.

20 With this and other objects in view the invention consists in certain novel features of construction, combination, and arrangement of parts, which will be hereinafter more fully set forth, and particularly pointed out in the 25 appended claim.

Referring to the accompanying drawings, Figure 1 is a side elevation of an incandescent electric lamp, illustrating the application 30 of my invention. Fig. 2 is a vertical sectional view through a portion of the lamp-socket and a portion of the base of the bulb, showing the two connected together by the spring-detent. Fig. 3 is a side elevation of the base of the bulb, and Fig. 4 is a detail perspective view 35 of the spring-detent.

In the drawings, 1 denotes the bulb of the lamp, 2 its base, and 3 the socket. The base instead of being screw-threaded has a smooth periphery and is formed near its upper end 40 with a horizontally-disposed slot 5. The socket is slit to form the spring-detent 6, having an inwardly-projecting toe 7, one end of which is beveled, as shown at 8. This toe is adapted to swing into the slot 5 of the base 45 when said base is inserted into the socket and hold the bulb in place. To disengage the base from the socket, the bulb is turned in the di-

rection of the arrow, which engages the end wall 5' of the slot with the beveled end of the toe and allows the slot to ride from engagement with the toe with a slight click and permit of the withdrawal of the base from the socket. A movement in the opposite direction when the parts are assembled is limited by a stud *a*, projecting laterally from the base, 55 coming in contact with the end wall *a'* of a recess *a*², formed in the lower edge of the socket, thus relieving the spring-detent of undue strain and preventing it from being broken, which would be very apt to be the 60 result should a person unfamiliar with this form of socket attempt to remove the lamp by turning it in the wrong direction. The stud *a* and the recess *a*² also serve as a guide to the eye in inserting the base within the 65 socket, inasmuch as when the stud *a* is vertically alined with the recess *a*² the slot is also alined with the toe of the spring-detent.

From the foregoing description, taken in connection with the accompanying drawings, 70 the construction, operation, and advantages of the invention will be readily understood without requiring an extended explanation. The device is exceedingly useful for the purpose for which it is designed and may be 75 placed upon the market at a comparatively small cost.

Various changes in the form, proportion, and the minor details of construction may be 80 resorted to without departing from the principle or sacrificing any of the advantages of this invention.

Having thus fully described my invention, what I claim as new, and desire to secure by Letters Patent, is—

In a lamp of the character described, the combination of the lamp-socket and a lamp-base, the one provided with a spring-detent having a toe and the other with a slot to receive said toe and lock the base to the socket, 90 and the one provided with a recess and the other with a coacting stud adapted to be brought into engagement with one of the end walls of the recess when the base is turned in

one direction, thus forming a stop and preventing the end wall of said slot engaging the toe and injuring the same, said detent being released by the rotation of the lamp-base with respect to the lamp-socket, substantially as described.

In testimony whereof I have hereunto set

my hand in presence of two subscribing witnesses.

ANDREW MCKENZIE.
